UNITED STATES PATENT OFFICE

FREDERICK C. SIMMONS, OF HIGHLAND PARK, PENNSYLVANIA, ASSIGNOR TO PIONEER SUSPENDER COMPANY, A CORPORATION OF PENNSYLVANIA

BEVELING

Application filed August 25, 1926. Serial No. 131,372.

The invention relates to improvements in beveling. The object is to provide improved methods and means for beveling flexible strips, especially the corners of the side edges 5 of leather belts, by abrasion.

The invention comprises method and means whereby the strip is supported and moved so that the corners of its side margins will cross the paths of travel of a plurality of abrading 10 devices.

The invention comprises a plurality of pairs of co-operating rollers, some or all being power driven, and associated supporting and guiding mechanism, for causing the strip or belt to travel in a desired path, and a plurality of grinding or abrading elements projecting partway into the path of travel of the belt, that is, projecting sufficiently into said path to abrade the upper and lower corners 15 of the side edges of the belt. These abrading elements are also power driven.

The invention also comprises means for supporting and adjusting these abrading elements, with respect to the path of travel of the body operated upon.

The invention also includes improvements in details of construction and operation.

Referring to the drawings, which illustrate merely by way of example, suitable means for 30 effecting the invention.

Fig. 1, is a side elevation.

Fig. 2, is a plan view.

Fig. 3, is a section on line 3, 3, of Fig. 2.

Fig. 4, is a section on line 4, 4, of Fig. 1.

Fig. 4^a is a vertical section of a pair of feed rollers, with an abrading wheel in elevation.

Fig. 5, is a section on line 5, 5, of Fig. 3.

Fig. 6, is a cross section, on an enlarged 40 scale, of the belt after treatment.

Similar numerals refer to similar parts throughout the several views.

In Figs. 1 and 3 are shown four pairs of cooperating rollers, these rollers are numbered 6, 7, 8, 9, 10, 11, 12 and 13, respectively.

The device herein illustrated and described, by way of example, is suitable for operating upon strips of leather used in the manufacture of belts for wearing apparel.

50 The strips are adapted to pass between the

rollers of each pair, and between the guide elements 14 and 15, positioned between the pairs of rollers and above and below the path of travel of the strips. The construction of the guide is shown in Fig. 5.

55

The several rollers are driven by gears 16, 17, 18, 19, 20, 21 and 22. Gear 16 is driven by sprocket 23, which is driven through the chain 24, from sprocket 25 on counter-shaft 26. Counter-shaft 26 is driven from a 60 sprocket on the reducing gear 27, which is driven by motor 28, as shown in Fig. 1.

This description refers to rollers 10 to 13 inclusive. Rollers 6 to 9 inclusive are driven by a similar set of gears 19' to 22' inclusive, 65 sprocket 23', chain 24' and sprocket 25' also on countershaft 26.

Fig. 1, shows the second, or B unit of rollers and the driving means, similar to the first 70 unit of rollers, except that the second unit is offset from the first, as shown in Fig. 2, and laterally adjustable as hereinafter described.

Flanking the several pairs of rolls are the grinding or abrading wheels, 30, 31, 32 and 75 33. Each abrading wheel is mounted in a suitable frame such as 34, shown in Figs. 1 and 2. These frames are adjustably mounted, by means of the screws and slots 34', on the machine and provide bearings for the shafts 35 of the abrading wheels. The adjustment of the frames 34 is secured by the adjusting screws 36, for adjusting the abrading wheels 80 with respect to the belt to be operated upon.

The grinding wheels 30 and 31, on one side 85 of the machine are mounted on shafts 35 provided with pulleys 39 and 40 driven by belts 41 and 42 from the counter-shaft 43 which is driven by belt 44 directly from the motor 28. Counter-shaft 43 also drives through belt 44', 90 the counter-shaft 45, which in turn drives wheels 32 and 33, which are on the other side of the machine, in a similar way.

One roller of each pair of rollers is arbitrarily movable and spring controlled, and 95 one roller of each has a fixed bearing. Referring to Figs. 1 and 3, roller 11 is mounted on a bifurcated arm 47, connected to hand lever 48, mounted on shaft 49, which lever 48 is controlled by spring 50, normally to 100

urge the roller 11 toward roller 10. The spring actuated movement of roller 11 is controlled by stop 51, adjustably secured by means of screw and slot 52. One roller of each pair is controlled in this way.

5 In a similar manner rollers 8 and 12 are mounted on bifurcated arms 46, controlled by hand levers 54 and springs 55. The stop plates 56 are adjustable and serve to limit 10 the movement of a roller towards its co-operating roller.

By the simultaneous operation of levers 48 and 54 the rollers of one unit may be separated for the purpose to be described.

15 For the purpose of adjusting the machine for different widths of belt, one unit is movable laterally toward or away from the line of the other unit. This is accomplished in the following way:

20 The unit, marked A, is fixed, and the unit marked B, is movable. The frame 57, carrying unit B is slidably mounted on a stationary part of the machine by the screws and slots 58. The frame 57 is provided with the lug 59, 25 co-operating with the suitably mounted screw 60, operated by the hand wheel 61, whereby the frame 57 of said unit B may be moved laterally toward or away from the longitudinal line of the fixed unit. This adjustment 30 may be arbitrarily made with a belt, of the width to be operated upon, in position. After such adjustment, by separating the rollers as above described, the guides of proper width are put in place.

35 The abrading wheels, 30 to 33 inclusive, are so positioned, two on each side of the train of rollers, that they will engage the upper and lower corners of each side edge of the belt, as said corners move through the paths of travel 40 of the peripheries of said abrading wheels.

It will be noted from an inspection of Fig. 2 that the rollers of one unit are in a line which is offset from the line of the rollers of the other unit, and that the belt 67 projects 45 on one side of the rollers of one unit and on the other side of the rollers of the other unit so that the edges of the belt may be engaged by the abrading wheels on the said projecting sides. It will also be noted from an inspection 50 of Figs. 2 and 4 that certain of the rollers are recessed sharply from their peripheries on the side from which the belt projects in order to receive the abrading wheel which projects into said recess, and thus the abrading wheel is permitted to engage the corner of the belt which projects from the side of said recessed roller as indicated in Fig. 4a. It will also be noted that the roller cooperating 55 with the recessed roller, projects laterally slightly beyond the side margin or face of the recessed roller, in order to support the belt opposite the corner being abraded and to prevent the belt from bending away from the abrading wheel.

60 These abrading wheels are so rotated, that

they cut or abrade into the flat part of the belt, and leave the belt at the edge thereof, so that the abrasion on the line of the flat part or surface is clean cut, and any feather that may be left, is left on the thin edge of the belt. This feather is easily removed by a subsequent operation.

65 Casings or hoods, such as 62, are fitted over the several abrading wheels and are connected by pipes such as 63, with a suitable 70 suction box 64.

What I claim is:

1. In a belt beveling machine, the combination of power driven cooperating pairs of rollers for moving the belt in the direction of its longitudinal extension, one of each pair of rollers provided with a recess in its face to allow the roller to support the work close to the marginal line of bevel without interfering with the abrading element, and rotating 80 abrading elements operating on the corners of the belt during its movement.

2. In a belt beveling machine, the combination of power driven cooperating pairs of rollers for moving the belt in the direction of its longitudinal extension, one of each pair of rollers provided with a recess in its face to allow the roller to support the work close to the marginal line of bevel without interfering with the abrading element, stationary 90 guides for the belt positioned between the pairs of rollers, and rotating abrading elements operating on the corners of the belt during its movement.

3. In a belt beveling machine, the combination of power driven cooperating pairs of rollers for moving the belt in the direction of its longitudinal extension, one of each pair of rollers having its face projecting beyond the face of the other roller and the other roller 100 provided with a recess in its face to allow the roller to support the work close to the marginal line of bevel without interfering with the abrading element, and rotating abrading elements operating on the corners of the belt 105 during its movement.

4. In a belt beveling machine, the combination of power driven cooperating pairs of rollers for moving the belt in the direction of its longitudinal extension, one of each pair of rollers provided with a recess in its face to allow the roller to support the work close to the marginal line of bevel without interfering with the abrading element, rotating 115 abrading elements operating on the corners of the belt during its movement, and means for adjusting the relative positions of the several pairs of rollers for different widths of belt.

5. In a belt beveling machine, the combination of power driven cooperating pairs of rollers for moving the belt in the direction of its longitudinal extension, one of each pair of rollers provided with a recess in its face to allow the roller to support the work close to 125

the marginal line of bevel without interfering with the abrading element, rotating abrading elements operating on the corners of the belt during its movement, and means for adjusting the position of each abrading element with respect to the depth of its abrading action.

6. In a belt beveling machine, the combination of power driven cooperating pairs of rollers for moving the belt in the direction of its longitudinal extension, one of each pair of rollers provided with a recess in its face to allow the roller to support the work close to the marginal line of bevel without interfering with the abrading element, rotating abrading elements operating on the corners of the belt during its movement, and means for adjusting the positions of the rollers and of the abrading elements for different widths of belt.

7. In a machine for beveling belts, the combination of means for moving the belt in a definite path of travel, said moving means comprising cooperating rollers adapted to clamp the belt on one side close to the marginal line of bevel, and on the other side close to the edge of the belt, and means for abrading the marginal corner thereby exposed during said travel, said abrading means operating upon the belt upon the line projected from the line of engagement therewith of said cooperating rollers.

FREDERICK C. SIMMONS.
